UNITED STATES PATENT OFFICE.

JOSEPH O. BEAZLEY, OF BALTIMORE, MARYLAND, ASSIGNOR TO THE BRUSH MOP WRINGER MANUFACTURING COMPANY, OF BALTIMORE, MARYLAND, A CORPORATION OF MARYLAND.

COMBINED MOP AND SCRUBBING-BRUSH.

977,064.

Specification of Letters Patent.

Patented Nov. 29, 1910.

Application filed June 26, 1909. Serial No. 504,565.

To all whom it may concern:

Be it known that I, JOSEPH O. BEAZLEY, a citizen of the United States, residing at Baltimore, State of Maryland, have invented a new and useful Combined Mop and Scrubbing-Brush, of which the following is a specification.

The invention relates to a combined mop and scrubbing brush.

The object of the present invention is to improve the construction of combined mops and scrubbing brushes, and to provide a simple, inexpensive and efficient device of this character, adapted to enable the operation of wringing a mop cloth to be performed with greater ease and facility than heretofore, and equipped with means for arranging a scrubbing brush either longitudinally or transversely of the device to enable the brush to be arranged for ordinary scrubbing and also to be secured in a projecting position for scrubbing in corners and similar places.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages of the invention.

In the drawings:—Figure 1 is a plan view of a combined mop and brush, constructed in accordance with this invention. Fig. 2 is a longitudinal sectional view of the same, the parts being arranged to form a mop. Fig. 3 is a similar view, the parts being arranged for scrubbing. Fig. 4 is a transverse sectional view on the line 4—4 of Fig. 1. Fig. 5 is a detail perspective view of the plate, which constitutes the body of the mop head. Fig. 6 is a transverse sectional view on the line 6—6 of Fig. 1. Fig. 7 is a detail perspective view, illustrating the construction of the locking and wringing shaft.

Like numerals of reference designate corresponding parts in all the figures of the drawings.

1 designates a plate or frame constituting

the body of the mop head, and designed to be constructed of suitable material. In the embodiment of the invention illustrated in the accompanying drawings, the plate 1 is stamped out of sheet metal for both lightness and cheapness, but it may consist of a casting, as will be readily understood. One of the faces of the plate is flat to form a backing for a mop cloth 2, which may be constructed of any suitable material and which is preferably in the form of a band, stretched to provide a cloth of two thicknesses and to enable its easy attachment to a front supporting loop 3, and a rear loop 4 of a wringing shaft 5, located, respectively, at the front and rear ends of the plate 1. The plate 1 is substantially oblong and extends longitudinally of the device, nearly the entire length of the mop.

The front loop is constructed of a single piece of stout wire, rod metal, or similar material, and it is provided with longitudinal arms 6, located at opposite sides of the plate 1 and having their terminals 7 bent inward, and forming lateral projections, which engage openings in attaching lugs 8, located at opposite sides of the rear portion of the plate and formed integral with the same. The lugs 8 are bent at substantially right angles to the body portion of the plate, which is also provided at an intermediate point with opposite bracing lugs 9, located at opposite sides of the said plate, and arranged at the outer faces or edges of the arms, and adapted to prevent the same from spreading and becoming accidentally disengaged from the inner or rear attaching lugs 8. The arms 6 diverge slightly toward the rear end of the plate, and the bracing lugs 9 are set at a slight angle to conform to the angle of the arms. The front loop 3 is bent at an angle to the arms to locate its transverse mop cloth-receiving portion close to the plane of the flat face of the plate, so that the mop cloth will present a continuous flat outer face for engaging the floor, or other surface to be cleaned. The rear terminals of the arms of the front loop may be readily detached from the lugs 8, when it is desired to connect the front loop with or disconnect it from a mop cloth.

The rear loop 4, which is open at one side, is formed integral with the wringing shaft

5, which is constructed of suitable metal similar to the front loop. The wringing shaft 5, which is provided at its rear end with a handle loop 10, is journaled in bearings 11 and 12 of front and rear alined arms 13 and 14 of a bracket 15, which preferably consists of a casting. The body portion of the bracket 15 consists of a sleeve, fitted on the front end of a handle 16 and provided 10 at opposite sides with front and rear laterally projecting tubular extensions 17 and 18, forming attaching means for resilient connecting rods 19. The sides of the sleeve or body portion of the bracket 15 are preferably open, as shown, and the inner or rear portions of the connecting rods, which are located at opposite sides of the handle, pass through the front lateral extensions 17 and have laterally bent terminals 20, arranged in the rear extensions 18 and projecting through side openings 21 thereof.

The shaft 5 has sufficient length to permit a limited longitudinal movement of the same in its bearings 11 and 12 to compensate for the shortening of the mop cloth, when the latter is twisted during the operation of wringing the same, and the rear supporting arm 14 is provided at the bearing 12 with a plurality of notches or recesses 22, adapted to be engaged by the handle 10 for locking the shaft against backward movement, when rotating the same to wring the mop. When the shaft is rotated to wring the mop, one hand grasps 35 the handle of the mop and the other the handle of the shaft, and the latter is turned a portion of a revolution and is engaged with the notches to prevent the shaft from rotating backward while the operator is removing his hand from the shaft and regrasping the handle thereof for further rotation of the shaft. This will enable the wringing of the mop cloth to be accomplished with great facility.

45 The connecting rods have their front or outer terminals 23 bent laterally in opposite directions and engage with openings of ears 24, formed integral with the plate 1, and located at opposite sides thereof at a point 50 intermediate of the ends of the same. The ends 23 of the connecting rods cross and extend beyond the arms of the front loop, so as to operate as means for holding the front loop in proper position with relation to the plate. The connecting rods 19 are resilient 55 to enable the laterally projecting terminals 23 to be readily engaged with and disengaged from the ears 24, and the said rods are bent slightly at an intermediate point at 60 25 to arrange the handle at the proper angle to the plate 1 to obviate the necessity of the operator stooping, when using the combined mop and brush.

65 The handle is adapted to be arranged at an obtuse angle to either face of the plate 1,

and when it is arranged at an obtuse angle to the flat mop cloth-receiving face of the plate 1, as illustrated in Fig. 2 of the drawings, it is held in such position by an upstanding arm 26, extending between the connecting rods, so as to engage with one or both of the same at the inner sides or faces thereof. In the accompanying drawings I have shown the upstanding arm engaged at one side only with the adjacent connecting 75 rod, but it is obvious that it may be made of sufficient width to interlock with both of them. The interlocking of the upstanding arm with one of the rods is preferable, however, as it is sufficient to hold the handle and the plate in proper angular relation. The arm 26 is provided at its engaging side with a notch 27 to receive the co-acting connecting rod 19. A plurality of notches 27, however, may be provided to afford an adjustment of the handle, if desired.

When it is desired to arrange the handle 16 of the device at an obtuse angle to the other face of the plate 1, the connecting rod 19 is disengaged from the upstanding arm 26, and the mop head or plate 1 is reversed, and the said connecting rods 19 are engaged with inwardly projecting lugs 28 of the inner or rear end of the plate 1. The plate 1 is provided at its rear end with opposite 90 longitudinal slots 29, which permit the connecting rods 19 to be engaged with and disengaged from the lugs 28. The resiliency of the connecting rods will maintain them in engagement with the lugs, when the device is arranged to permit the use of a scrubbing brush 30.

The scrubbing brush 30, which may be arranged either transversely or longitudinally of the plate 1, as illustrated in dotted lines in Fig. 1 of the drawings, is secured in its adjustments by means of a transversely disposed clamping jaw 31, and opposite side lugs 32 and 33, the lug 33 being equipped with a clamping screw 34, mounted in a threaded perforation of the lug 33. The lugs 32 and 33 are formed integral with the plate 1 at opposite sides of the front end thereof, and when the brush is arranged longitudinally of the plate, it is placed between the side lugs 32 and 33 and is clamped by the screw 34. The side lugs are provided at their inner or rear edges with notches 35 to engage with the brush when the latter is arranged transversely of the plate. The head or back of the brush is provided in its edges with a groove 36, which is engaged with the lugs 32 and 33 when the brush is arranged transversely of the plate 1, as illustrated in Fig. 2 of the drawings. The screw 34 also engages the groove at one side of the back of the brush when the latter is arranged longitudinally of the plate 1.

The jaw 31 is located in rear of the brush and is engaged with the same, when the lat- 130

ter is arranged either longitudinally or transversely, and it is provided at its front engaging face with projections 37, and it has a reinforcing rib 38 at its rear face. It 5 is adjusted toward and from the brush to engage and release the same by means of a longitudinal adjusting screw 39, mounted in openings of alined bearing lugs 40 and 41 and in a bearing opening 42 of the upstanding 10 arm 26. The lug 40 is located at the front end of the plate, and the lug 41 is located at a point intermediate of the ends of the same and formed integral with the said plate, which is also provided with openings, 15 as clearly illustrated in Figs. 1 and 5 of the drawings to lighten the construction. The head of the adjusting screw is located at the rear end of the plate 1 in convenient position for easy manipulation, and it fits 20 against the rear face of the upstanding arm 20. The longitudinal adjusting screw, which is provided at its rear end with a suitable head 43, is also equipped with collars 44 and 45, arranged at the front face of the front 25 bearing lug 40 and at the rear face of the intermediate bearing lug 41 to hold the screw against longitudinal movement with relation to the plate. The screw 39 is provided between the bearing lugs 40 and 41 30 with screw threads 46, which engages a threaded opening 47 of an enlargement 48 of the jaw. When the screw is rotated, the transversely disposed jaw is moved backwardly and forwardly in a direction longitudinally of the plate 1, and it is guided 35 and braced in such movement by means of parallel longitudinal flanges 49, formed integral with the plate 1 and located at opposite sides of the front portion thereof, as 40 clearly illustrated in Fig. 1 thereof. The side flanges 49 also form a solid support for the back of the brush.

Having thus fully described my invention, what I claim as new and desire to secure by Letters Patent, is:—

1. A device of the class described including a mop head, clamping devices arranged at one of the faces of the mop head for holding a brush, means mounted on the mop head for holding a mop cloth at the other face of the same, a bracket comprising a sleeve and provided with alined arms and having inner and outer laterally projecting tubular extensions, the inner tubular extensions being provided with side openings, a handle secured in the sleeve, rods passing through the tubular extensions and engaging the said openings, said rods being connected with the mop head and adapted to be 50 arranged at an angle to either face of the same, and a wringing shaft supported by the said arms and provided with means for connecting it with a mop cloth.

2. A device of the class described including a mop head provided with opposite lat-

erally extending lugs, a handle having longitudinal connecting rods hinged to the mop head and adapted to swing with respect thereto to arrange the handle at an angle to either face of the mop head, said rods being 70 arranged to engage detachably with the lugs for securing the handle in one position, means arranged at one of the faces of the mop head for holding a brush, and means mounted on the other face of the mop head 75 for the attachment of a mop cloth.

3. A device of the class described including a mop head provided with spaced slots and having laterally extending lugs located at the said slots, a handle provided with longitudinal connecting rods hinged to one side of the mop head and arranged to swing into the slots and to project to the other side of the mop head and engaged with the lugs to hold the handle in position, means arranged 80 at one of the faces of the mop head for holding a brush, and means mounted on the other face of the mop head for the attachment of a mop cloth.

4. A device of the class described including a mop head provided with an upstanding arm having an engaging portion, a handle provided with spaced connecting rods hinged to the mop head and adapted to swing with respect thereto to arrange the 90 handle at an angle to either face of the mop head, one of the rods coöperating with the said engaging portion of the upstanding arm to secure the handle in one position of its adjustment, means arranged at one face of 100 the mop head for holding a brush, and means mounted on the other face of the mop head for the attachment of a mop cloth.

5. A device of the class described including a mop head provided with a slot and having a lug at one side of the slot, said mop head being also provided at the opposite side with an upstanding arm having engaging means, a handle having a connecting rod hinged to the mop head at one side thereof 110 and adapted to be arranged at an angle to either face of the same and arranged to engage either the lug or the upstanding arm to secure the handle in its different positions, means arranged at one of the faces of the 115 mop head for holding a brush, and means mounted on the other face of the mop head for the attachment of a mop cloth.

6. A device of the class described including a mop head provided at its front end with brush-engaging lugs and having brush-supporting flanges extending rearwardly therefrom, a clamping jaw movable along the flanges and coöperating with the said lugs, means for actuating the clamping jaw, 125 a front mop cloth-receiving loop having sides extending beneath the jaw and connected with the head, a handle having rods connected with the head and engaging the arms of the front loop, and a wringing shaft 130

carried by the handle and having means co-operating with the front loop for holding a mop cloth.

7. A device of the class described including a mop head, clamping devices arranged at one of the faces of the mop head for holding a brush, means mounted on the other face of the mop head for the attachment of a mop cloth, a handle having a connecting rod hinged to the mop head and arranged to swing with respect thereto to set the handle

at an obtuse angle to either face of the mop head, and means mounted on the mop head for securing the handle in rigid relation with the mop head.

In testimony, that I claim the foregoing as my own, I have hereto affixed my signature in the presence of two witnesses.

JOSEPH O. BEAZLEY.
